RAZOR BLADE SHARPENER

Eric Olson, Beloit, Wis.

Application December 6, 1946, Serial No. 714,524

5 Claims. (Cl. 51—158)

1

This invention relates to blade sharpening devices, and more particularly to a device for sharpening safety razor blades of the double-edge type.

A main object of the invention is to provide a novel and improved razor blade sharpening device which is very simple in construction, easy to use, and efficient in operation.

A further object of the invention is to provide an improved razor blade sharpener which is inexpensive to manufacture, neat in appearance, and compact in size.

Further objects and advantages of the invention will become apparent from the following description and claims, and from the accompanying drawings, wherein:

Figure 1 is a vertical longitudinal cross-sectional view taken through a razor blade sharpening device according to the present invention.

Figure 2 is a plan view, with its top cover removed, of the blade sharpening device of Figure 1.

Figure 3 is a side elevational view of the sharpening device of Figure 1.

Figure 4 is a vertical transverse cross-sectional view taken on line 4—4 of Figure 1.

Figure 5 is a perspective detail view of a hone plate member employed in the blade sharpening device of Figure 1.

Figure 6 is an enlarged detail view, partly in cross-section, of the blade engaging portion of the blade oscillating arm employed in the sharpening device of Figure 1.

Referring to the drawings, 11 designates a generally rectangular base member provided with a depending transverse leg 12 adjacent each end thereof to support base member 11 in raised relation to a subadjacent supporting surface.

The top surface of base member 11 is recessed at 13, and journaled transversely in the side walls of the recessed portion 13 is a crank shaft 14, the cavity 13 being further recessed at 15 to provide rotative clearance for the crank portion of crankshaft 14. Keyed to one end of crankshaft 14 is an operating crank 16, said crank being pivoted to the crankshaft at the keyed connection thereof so that the crank may be folded flush against the adjacent side edge of base 11 when the blade sharpening device is not in use.

Rotatively engaged with the crank portion of crankshaft 14 is the recessed rear end of a forwardly extending arm 17, the forward end of said arm being formed with a downwardly directed leg 18. The end of leg 18 is transversely grooved, and secured in the groove is a resilient foot member 19 of rubber or the like. Foot member 19 is

formed with a flange portion 20 and a stud portion 21. Stud portion 21 is shaped so as to fit into the intermediate portion of the center recess of a standard double-edged razor blade with the flange portion 20 overlying the surface of the blade adjacent said center recess, thus being interlocked with the blade for imparting longitudinal movement thereto, responsive to rotation of crankshaft 14.

10 Pivotedly secured to the intermediate portion of arm 17 is a depending rod member 22 which extends downwardly through a flared opening 23 formed in base member 11. Threaded on the lower end of rod member 22 is a knurled nut 24, and encircling the rod member between nut 24 and the bottom surface of base member 11 is a coiled spring 25 which provides downward tension on the rod member, said tension being adjusted by nut 24 to a desired value. A suitable bearing washer is positioned between the top of spring 25 and the adjacent bottom surface of base member 11.

25 The base member 11 is formed at its forward position with a rectangular recess 26, and secured in the forward portion of the recess is an up-standing projection 27 which defines with the walls of recess 26 a square seat. Removably positioned in the square seat thus defined is a square hone plate member 28 which is symmetrically concaved on both sides as shown at 29, 29, whereby the plate may be employed on either its top or bottom side. Hone plate member 28 may be positioned with its concaved portions 29, 29 extending either longitudinally or transversely with respect to base member 11.

30 35 Removably secured to the rear end portion of base member 11, as by a dovetailed connection, is a cover member 30 formed with an internal cavity 31 which overlies the crankshaft 14 and the rearward portion of arm 17. Cover member 30 is preferably smoothly curved in outer contour so as to provide a streamlined appearance.

40 45 In operation, a blade is placed on the hone plate member 28 and its central recess is interlocked with the resilient foot member 19. Arm 17 may be lifted sufficiently to position the blade on the hone plate member as thus described.

Crank 16 is then rotated, which causes the blade to oscillate forwardly and rearwardly on the hone plate member, the edges of the blade being in contact with the concave surface of the hone. The pressure on the blade may be regulated by adjusting knurled nut 24. After the blade is sharpened, it may readily be removed by lifting arm 17, as shown in dotted view in Figure 1,

and disengaging the blade from the resilient foot member 19.

In the position of the hone plate 28 shown in Figures 1 and 2, the blade moves longitudinally with respect to the concave surface 29 during the sharpening process. The hone plate may be turned 90° so that the blade moves transversely with respect to said concave surface to provide a different type of sharpening action, as shown in Figure 3.

When one surface of the hone plate is worn beyond further usefulness, the plate may be turned over and used on the other side, thus extending the life of the hone.

While a specific embodiment of a razor blade sharpening device has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. A razor blade sharpening device comprising a base member, a crankshaft journaled in said base member, an arm connected to said crankshaft for reciprocating movement responsive to rotation of said crankshaft, a resilient foot member carried by said arm adapted to interlock with a razor blade, a hone plate carried on said base member beneath said foot member, and spring means biasing said arm downwardly whereby said foot member exerts pressure on said hone plate.

2. A razor blade sharpening device comprising a base member, a crankshaft journaled in said base member, an arm connected to said crankshaft for reciprocating movement responsive to rotation of said crankshaft, means carried by said arm adapted to interlock with a razor blade, a hone plate carried on said base member beneath said foot member, and spring means biasing said arm downwardly whereby said foot member exerts pressure on said hone plate.

40

4
a hone element on said base member subadjacent to said means, and spring means biasing said arm downwardly.

3. A razor blade sharpening device comprising a base, a crankshaft journaled in said base, an arm connected to said crankshaft for reciprocating movement responsive to rotation of said crankshaft, means carried by said arm adapted to interlock with a razor blade, a square hone plate, said base plate being formed subadjacent said means with a recess shaped to snugly receive the hone plate, and spring means biasing said arm downwardly.

4. A razor blade sharpening device comprising a base, a crankshaft journaled in said base, an arm connected to said crankshaft for reciprocating movement responsive to rotation of said crankshaft, means carried by said arm adapted to interlock with a razor blade, a square hone plate, said plate being concaved on both sides, said base plate being formed subadjacent said means with a recess shaped to snugly receive the hone plate, a tension element pivotally secured to and depending from said arm, and means exerting downward spring pressure on said tension element.

5. A razor blade sharpening device comprising a base, a crankshaft journaled in said base, an arm connected to said crankshaft for reciprocating movement responsive to rotation of said crankshaft, a depending leg carried by said arm, a rubber foot element carried by said leg, said element being shaped to interlock with a razor blade, a hone element on said base subadjacent said element, a tension member pivotally secured to and depending from the intermediate portion of said arm, and means exerting downward spring pressure on the lower end of said tension member.
